CLAIM

The ornamental design for a holder for elastic hair bands, as shown.

DESCRIPTION

FIG. 1 is a front plan view of a holder for elastic hair bands, showing my new design in an environment of use;

FIG. 2 is a front plan view with the environment removed;

FIG. 3 is a top view thereof, the bottom being identical; and,

FIG. 4 is a right side view, the left side being identical.

The hands and hair bands shown in broken lines in FIG. 1 are for the purposes of illustrating environment, and form no part of the claimed design.
